UNITED STATES PATENT OFFICE.

PAUL F. HESSE, OF PAWTUCKET, RHODE ISLAND.

APPAREL COLLAR.

Application filed March 15, 1926. Serial No. 94,847.

This invention relates to apparel collars and, particularly to the so-called soft turned-down collars which have a sufficient degree of inherent stiffness to render them self-supporting so that they may be worn without starching.

Most collars of this type are made up either of several layers of fabric stitched together, or of strips of multiply fabric having the several plies interwoven with binder threads. The former type of folding collar has never been entirely satisfactory owing to its flimsy appearance and insufficient inherent stiffness to prevent it from wrinkling and "wilting" under the effect of perspiration when worn. Multiply fabric collars possess the necessary inherent stiffness and self-supporting characteristics and have become extremely popular for gentlemen's wear, but this latter type of collar is relatively expensive to manufacture and must be sold at a considerably higher price than the multi-layer type of collar, either of the soft or starched variety.

It is therefore one object of the present invention to provide a collar devoid of the flimsy character of the ordinary multi-layer soft collar and having all the attributes of the more popular multiply collar, yet capable of being manufactured at much less cost than the latter.

To provide the improved collar of the type specified the present invention contemplates the use of a peculiar character of weave to produce a relatively thick yet pliable fabric, which, when incorporated in the collar, gives the required degree of stiffness thereto so that it will be self-supporting without additional reinforcing means and also capable of resisting the wilting tendency from dampness.

The following specification describes several methods of carrying out the invention, and the accompanying drawings illustrate the preferred embodiment thereof. In the drawings:

Fig. 1 is a plan view showing a collar of conventional shape in its flat form, as illustrative of one embodiment of the invention;

Fig. 2 is an enlarged sectional view taken on line 2-2 of Fig. 1 and illustrating a preferred method of joining the two folding parts of the collar, and also the manner of

forming the fold line or folding guide in the fabric;

Fig. 3 is a similar view showing another method of providing a fold line or guide;

Fig. 4 is a very much enlarged and more or less diagrammatic view showing the character of the preferred weave employed for the present improved type of collar;

Fig. 5 is an enlarged sectional or profile view of the preferred weave structure; and

Fig. 6 is a greatly magnified perspective view showing the weave partly in section.

As illustrated in Fig. 1 of the drawings the present type of collar comprises a neckband 2 and an outer portion or exposed panel 3 adapted to fold down around the neckband. The complete collar may be woven in one piece, but preferably it is made up of two strips of fabric, one for the neckband 2 and the other for the outer panel 3. When constructed in two pieces the neckband 2 is preferably woven with a two-ply strip 4, 4 extending along its upper edge, whereby to provide a reentrant channel or opening 5 into which is inserted the selvedge edge 7 of the other strip of fabric which forms the outer panel 3 of the collar, see Fig. 2. With this construction of the collar the double-ply portion of the neckband 2 overlaps both sides of the selvedge edge of the panel 3 and is secured thereto by several rows of stitches indicated at 8.

It is desirable to provide means to adapt the outer panel 3 of the collar to fold smoothly and evenly on a line contiguous to its joinder with the neckband 2, and for this purpose any suitable fold line or folding guide may be incorporated in the fabric of the collar. A preferred method of providing the fold line is described and illustrated in my pending application for U. S. Patent Serial No. 518,531, filed November 29, 1921. The invention of this prior application consists in providing a fold line constituted by a twill weave extending in a narrow strip or band 9 longitudinally of the upper edge of the outer panel 3 of the collar.

In this twill-strip the threads are woven on a bias to provide a more flexible folding portion, which, nevertheless, is constituted by the same number of threads or yarns as the body of the collar so that the strength and wearing quality of the fabric is preserved. In other words, the fabric is not

weakened or reduced by eliminating any of the threads and therefore the completed collar will not deteriorate unduly from wear or from the repeated action of folding or bending it.

As another means for providing the fold line or guide for the collar I may incorporate in the fabric an enlarged cord 10, as illustrated in Fig. 3 of the present drawings and 10 more fully described in my United States Letters Patent No. 1,545,187, dated July 7, 1925. It is to be understood, however, that the method or means for providing the fold line which extends longitudinally of the top 15 of the main or outer panel 3 of the collar is not essential to the present invention, as any preferred practice may be adopted for this purpose.

As before stated, the present invention 20 resides in the peculiar character of the weave of the fabric employed in the manufacture of collars of the type specified, and Fig. 4 illustrates diagrammatically a preferred method of intermeshing the yarns in the 25 weave to secure the desired result. In this view the reference characters 12 and 13 designate the warp ends or yarns running longitudinally of the fabric, and longitudinally of the strip or strips which form the 30 collar; while the lateral weft or filling threads are designated 14. To provide a fabric of the required thickness and stiffness I incorporate therein alternate tight and slack warp threads intermeshed with the 35 weft yarns in any suitable order and functioning in the manner as later explained.

In accordance with the preferred character 40 of weave as illustrated in Fig. 4 of the drawings, the tight warp ends 12 are combined in pairs, or, in other words, woven double to increase the bulk and thickness of the fabric. Each pair of tight warp ends 12 may be considered as a single yarn however, for in some instances I may employ a single end of 45 coarser or heavier yarn in place of the two ends. In either case the single or double tight warp ends 12 alternate with the slack warp ends 13 which are woven relatively loose, as indicated in Fig. 4. The picks of 50 filling 14 are preferably interwoven with the warp ends in alternate order, that is under and over the alternate tight and slack warp ends, but the order of the weave may be varied to some extent if desired. It will be 55 understood that Fig. 4 illustrates the weave in open mesh, that is with the yarns widely spaced apart, whereas as a matter of fact in the finished fabric the yarns will be woven close together and tightly compacted.

60 Fig. 5 illustrates the weave in cross-section or profile and shows the filling or weft threads 14 more closely spaced, although not beaten up into the relation which they 65 assume in the finished fabric. This view more clearly illustrates the arrangement of

the threads in the weave, and indicates the manner in which the tight warp threads cooperate with the slack warp ends to give the body and thickness to the cloth. It will be observed by reference to this view that the 70 slack warp threads 13 pass over and under the weft threads 14 in loops which run substantially perpendicular to the face of the cloth, while the tight warp ends 12 are drawn taut to separate and support the weft 75 threads in two distinct planes, one on each face of the goods. The two tight warp threads 12 are shown in Fig. 5 as disposed one above the other, and this is substantially the position that the two ends of each pair 80 assume when the filling is beaten up at the fell of the cloth during the weaving operation.

Fig. 6 is a highly magnified view illustrating more accurately the disposition and arrangement of the threads in the finished fabric. It will be observed from this view that the weft threads 14 are beaten up into close juxtaposition and that they lie in two 85 opposite parallel planes corresponding substantially to the two opposite faces of the cloth. The slack warp yarns 13 are looped back and forth over these two sets of weft ends 14 in such manner that they form 90 "floats" extending at substantially right-angles to the face of the fabric. Extending longitudinally of the fabric and parallel with its opposite faces are the tight warp 95 ends 12 which form an intermediate separating medium for the two sets of filling threads on the opposite faces of the fabric. That is to say, the tight warp ends 12 provide a sort of filler for the fabric to space the weft ends in two opposite planes whereby 100 to give thickness and body to the cloth. It has been noted that the tight warp ends are 105 preferably woven double in order to increase their effect in separating the weft ends to thicken the fabric, but in other cases I may employ a coarser or heavier yarn for the tight warp ends. For example, where I have obtained most satisfactory results by weaving the tight warp ends double with a 26/2 yarn, I may employ a single end of 110 13/2 yarn to obtain substantially the same 115 result.

It will be noted from Fig. 6 that the surface of the cloth has a more or less ribbed or corded appearance, somewhat like a piqué fabric, due to the alinement of the 120 rows of loops of the slack warp threads 13 across the face of the goods, this effect being somewhat exaggerated in the drawing. In practice, while the fabric shows this 125 ribbed effect on its face in its rough or unfinished state, when the cloth is calendered or ironed its surface will become substantially smooth.

With the preferred character of weave as 130 above explained the fabric is given a greater

thickness and body whereby it is equal, if not superior, to the usual multiply fabrics as heretofore used for collars of the present type. On the other hand, the present type of fabric is much more economical to weave, due to the less number of warp and weft threads required to the inch in the goods, and also because the weave is much simpler and less difficult to produce. Where in multiply fabrics it is necessary to weave approximately 216 ends of warp and 104 to 108 picks to the inch to secure the desired result, in my present improved weave equally good results may be obtained with 180 warp ends and 84 to 88 weft picks to the inch. In fact, I am enabled to make a reduction of from 20 to 25 per cent in the whole number of ends required. Moreover, by employing coarser yarns I save approximately 40 per cent in the cost of the fine counts used in multiply fabrics. As another advantage, the present weave can be produced with less care and attention on the part of the weaver, and less liability of breaks, requiring piecing up, so that there are fewer stoppages in the weaving and consequently a higher rate of production can be maintained. The only change required from the ordinary weaving process is to provide separate sets of warps delivering from different beams, with one set maintained under a maximum tension and the other set allowed to float more or less loosely through the fabric.

It has been stated that the improved collar illustrated in Fig. 1 may be made either from a single piece of fabric, or from two strips joined together at their longitudinal edges as illustrated in Figs. 2 and 3 of the drawings. The fabric for the collar may be stretched over conical or fluted rolls during the weaving process, as is the usual practice, to impart to it a curvilinear set to adapt the collar to fold on a curvilinear line, whereby it will assume a smoother and neater appearance in use. Where the collar is made in one piece the whole fabric may be of the improved weave herein described, but in other cases when made in two pieces the parts may be of different weaves. As shown in Fig. 1, the finished collar is provided with the usual button-holes 15 and its edge may be hemmed or bound with an overlying strip in accordance with the common practice.

It will be observed that my invention provides an improved apparel collar of the type specified wherein the fabric has the required body and stiffness peculiar to multiply fabric collars, to render it capable of being folded smoothly and to be worn unstarched while yet preserving its neat and unwrinkled appearance. Furthermore, my improved collar can be manufactured by a simple weaving process for the fabric,

which, while producing the desirable and necessary attributes of a multiply fabric collar, is, at the same time, much more economical to manufacture. My improved collar also possesses the quality of greater durability and will not deteriorate rapidly from repeated foldings or from continued wear.

While I have herein described and illustrated a preferred embodiment of the invention, it will be understood that various modifications may be made both in the method of weaving the fabric and in the manner of forming the collar therefrom without departing from the spirit or scope of the invention. Therefore, without limiting myself in this respect, I claim:

1. An apparel collar constituted by one or more strips of single ply fabric composed of warp and weft threads of substantially the same size, the weft threads being disposed in two separate planes on the opposite sides of the fabric with those in each plane arranged in close juxtaposition, the warp threads being interwoven with the weft threads with certain of said warp threads drawn tight to separate the weft threads into the two planes, and certain other warp threads being left slack and looped back and forth around the weft threads with portions extending substantially perpendicular to the face of the fabric whereby the structure of the weave imparts body and thickness to the fabric to render the collar inherently self-supporting when folded. 100

2. An apparel collar of the soft folded type constituted by one or more strips of single ply fabric having a structure comprising lateral weft threads and longitudinal warp threads of substantially the same size, the alternate weft threads being separated into two distinct planes by means of tight warp threads extending therebetween and said weft threads disposed in close juxtaposition on the opposite sides of the fabric, and loose warp threads alternating with the tight warp threads and passing over and under the weft threads to bind them into the fabric with portions of said loose warp threads extending substantially perpendicular to the face of the fabric, and the whole forming a structure of such thickness as to give body and stiffness to the collar to render it inherently self-supporting. 110

3. As a new article of manufacture, an apparel collar constituted by one or more strips of single ply fabric having a structure composed of weft threads and warp threads of substantially the same size, with the weft threads separated into two planes and disposed in close juxtaposition on opposite faces of the cloth by means of tight warp threads extending between the two 120

- sets of weft threads of the opposite planes and serving as a filler for the cloth, and other warp threads looped back and forth around the individual weft threads of the
- 5 two sets in the opposite planes whereby to bind them into the structure and provide a fabric having sufficient body and thickness to render the collar inherently self-supporting.
- 10 4. As a new article of manufacture, an apparel collar of the soft folded type constituted by one or more strips of single ply fabric comprising warp and weft threads of substantially the same size, the warp
- 15 threads being alternately tight and slack and intermeshed over and under alternate

weft threads with the tight warp threads separating the latter into two distinct planes and serving as a filler for the fabric, the weft threads in both planes being arranged 20 in close juxtaposition on opposite faces of the fabric with the slack warp threads looped back and forth thereover and all of the threads compacted into a close weave to impart body and stiffness to the fabric 25 whereby to render the collar inherently self-supporting without starch or other added stiffening means.

In testimony whereof I affix my signature.

PAUL F. HESSE.
